UNITED STATES PATENT OFFICE.

AUGUSTUS STEIGER COOPER, OF SANTA BARBARA, CALIFORNIA.

CARBON BLACK AND METHOD OF PRODUCING SAME.

1,423,193.

Specification of Letters Patent. Patented July 18, 1922.

No Drawing.

Application filed January 19, 1922. Serial No. 530,376.

To all whom it may concern:

Be it known that I, AUGUSTUS STEIGER COOPER, a citizen of the United States, residing at Santa Barbara, in the county of Santa Barbara and State of California, have invented certain new and useful Improvements in Carbon Black and Methods of Producing Same, of which the following is a specification.

10 This invention relates to the method of producing carbon-black and to the product itself and which is to be ultimately used in various industrial arts.

I employ as the basis of my process and 15 for the raw material from which my commercial product is produced brown friable bitumen which is a natural product found intermixed with sand in certain portions of California.

20 Brown friable bitumen has never before been employed commercially for any useful purpose, and it has been discovered that this substance heretofore generally regarded as useless, is available for the production of an efficient commercial product in the form of a carbon-black.

In other words, by my process a natural product heretofore regarded as useless, is converted to a commercial product which 25 can be shipped and stored, and ultimately used for many purposes.

In California, United States of America, there are sands containing brown friable bitumen. These deposits consist of grains 30 of quartz sand varying in fineness. They resemble the quartz sand usually found on the present beaches of California; the grains are more or less rounded.

35 Hardness of sand grains..... 7
Specific gravity of grains..... 2.50

The interspaces in these sands are filled or partly filled with brown friable bitumen. In many of the deposits the only cement that 40 holds the grains of sand together is the brown friable bitumen. The adhesion of the brown friable bitumen to the sand grains is not very strong. The brown friable bitumen in the sand can be crushed between 45 the fingers.

50 Hardness of the brown friable bitumen, less than.. 1
Specific gravity..... 1 to 1½

Owing to the difference of the hardness between the sand and brown friable bitumen, 55 and the slight adhesion of the brown friable bitumen to the grains of sand, it is possible by crushing, impact and scouring the sand, that it can be reduced to grain and the brown friable bitumen disunited from the sand grains, and owing to the great difference 60 between the specific gravity of the sand and the specific gravity of the brown friable bitumen, the bitumen can be separated from the sand by air currents. 65

Heretofore this brown friable bitumen was considered of no value; thousands of tons were stripped from the viscous bitumenized sand that was used for paving, etc., and thrown on the waste dump. This manner of disposing of the sand containing 70 brown friable bitumen has been going on for more than forty years.

My methods or processes are as follows:—

After mining, the sand, containing the 75 brown friable bitumen, by the use of grinders, disintegrators and scourers, it is reduced to grain and the brown friable bitumen to an impalpable powder, the powdered bitumen is then separated from the sand by air 80 currents.

Then the powdered brown friable bitumen is subjected to the action of heat and thereby calcined to form the final product carbon-black. 85

What is claimed is:—

1. The process of producing carbon-black consisting of subjecting brown friable bitumen to a dry heat. 90
2. The product of carbon-black formed by calcining brown friable bitumen. 95
3. The process of producing carbon-black consisting of separating natural brown friable bitumen from sand and finally calcining the same. 100
4. The method of producing carbon-black, consisting of grinding brown bitumen bearing sands, blowing the bitumen therefrom, and heating the finely comminuted bitumen thus obtained to form a carbon-black.

In testimony whereof I affix my signature.

AUGUSTUS STEIGER COOPER.
